CLAIM

The ornamental design for a display screen with transitional icon, as shown and described.

DESCRIPTION

FIG. 1 is a first image according to a first embodiment in a sequence of a display screen with a transitional icon, showing the new design;

FIG. 2 is a second image according to the first embodiment thereof;

FIG. 3 is a third image according to the first embodiment thereof;

FIG. 4 is a fourth image according to the first embodiment thereof;

FIG. 5 is a fifth image according to the first embodiment thereof;

FIG. 6 is a sixth image according to the first embodiment thereof;

FIG. 7 is a seventh image according to the first embodiment thereof;

FIG. 8 is an eighth image according to the first embodiment thereof;

FIG. 9 is a ninth image according to the first embodiment thereof;

FIG. 10 is a first image according to a second embodiment in a sequence of a display screen with a transitional icon, showing the new design;

FIG. 11 is a second image according to the second embodiment thereof;

FIG. 12 is a third image according to the second embodiment thereof;

FIG. 13 is a fourth image according to the second embodiment thereof;

FIG. 14 is a fifth image according to the second embodiment thereof;

FIG. 15 is a sixth image according to the second embodiment thereof;

FIG. 16 is a seventh image according to the second embodiment thereof;

FIG. 17 is a first image according to a third embodiment in a sequence of a display screen with a transitional icon, showing the new design;

FIG. 18 is a second image according to the third embodiment thereof;

FIG. 19 is a third image according to the third embodiment thereof;

FIG. 20 is a fourth image according to the third embodiment thereof; and,

FIG. 21 is a fifth image according to the third embodiment thereof.

The appearance of the transitional icon sequentially transitions between the images shown in FIGS. 1-9, between the images shown in FIGS. 10-16, or between the images shown in FIGS. 17-21.

The process or period in which one image transitions to another image forms no part of the claimed design.

The broken lines showing the display screen form no part of the claimed design.

The shaded areas of the drawings illustrate a contrast in appearance.
